UNITED STATES PATENT OFFICE.

JOSEPH LUCE, OF SALT LAKE CITY, UTAH.

CELL FOR THE PRECIPITATION OF METALS.

SPECIFICATION forming part of Letters Patent No. 629,134, dated July 18, 1899.

Application filed April 11, 1898. Serial No. 677,231. (No model.)

To all whom it may concern:

Be it known that I, JOSEPH LUCE, a citizen of the United States, residing at Salt Lake City, in the county of Salt Lake and State of Utah, have invented certain new and useful Improvements in Cells for the Precipitation of Metals; and I do hereby declare the following to be a full, clear, and exact description of the invention, such as will enable others skilled in the art to which it appertains to make and use the same.

My invention relates to an improvement in cells for the precipitation of metals from their solution by electrolysis; and it consists in a single cell in which the action is continuous and which is provided with means by which the electrolyte can be given either an up or down movement, combined with frames which have a rotary movement through the electrolyte and to which the cathodes are attached, as will be more fully described hereinafter.

The objects of my invention are to provide a single cell without the use of partitions or strainers of any kind; to locate the anodes in the bottom of the cell and to so construct them that the electrolyte can be given a constant up or down motion over or through them; to attach the cathodes to revolving frames, not only for the purpose of obtaining greater cathode and anode surfaces, but to bring the electrodes uniformly and symmetrically opposite each other; to keep the electrolyte constantly stirred up by means of the frames which carry the cathodes, and thereby make the action of the electrolyte more uniform, and to construct a single continuously-operating cell in which a greater amount of work can be done and with more ease than has heretofore been possible.

In the accompanying drawings, Figure 1 is a vertical section taken through a cell which embodies my invention. Fig. 2 is a plan view of the same. Fig. 3 is a horizontal section taken through the cell just above the anodes.

A represents an ordinary circular wooden water-tank, which is made water-tight by the usual process and is provided with a thick bottom D. This tank is provided with a lining of any suitable waterproof material B—such as cement, asphaltum, paraffin, or any other suitable material. Over the waterproof

lining is placed a covering of thin boards C for the purpose of holding the lining in place, and these boards have their lower ends to catch in a groove D' in the bottom D and have 55 their upper ends held in position by means of the iron rail P, that is placed on the top of the tank.

Extending up through the center of the tank is a hard-wood post E, which has a hole made 60 through its center, and passing through the bottom of the tank and the opening in the center of the post is a clamping-rod, the upper end of which extends a suitable distance above the post and forms a bearing for the 65 hub G. This bolt F and post E do not constitute a core and have no mechanical utility in giving a greater steadiness and solidity to the apparatus. They have no effect whatever as auxiliaries in the distribution of the 70 electric current or of the electrolyte nor in the action that the first may have upon the second.

Mounted upon the top edge of the tank A is the circular iron rail P, and mounted upon 75 the top of the bolt F is the hub of a wheel, which consists of the spokes H and the rim I. The spokes H are made of hard wood and serve not only to connect the hub G and the rim I, but as supports for the wooden ring M 80 and the cathode-frames. The rim I is provided at suitable points with vertical grooved rollers J, which travel upon the rail P, and the outer edge of the rim I is provided with a groove J', so as to receive a horizontal rotary 85 motion around the bolt F by means of a driving-cord or other suitable operating device.

Upon the top of the spokes H is placed a wooden ring M, and upon the top of this ring is placed the main conductor N of the cathode-electrode and which receives the current from the trolley O, which is connected with the circuit-wire V.

Secured to each of the spokes H is a cathode-electrode U, connected with the main circuit by the conductor N, and which is supported in place by the cathode-frames L, which are made of wood, iron, or any other suitable material. In addition to the frames L a series of hangers U' depend from the 95 electrodes U and in which are supported the 100 rods X', and these hangers and rods form sup-

ports, upon which are placed, in addition to the frames L, the cathode-electrodes, either in the shape of metallic plates or other substance, such as cloth, paper, wood, or other material impregnated or lined with metallic compounds, or powders, or graphite, or other substance convenient for precipitation of the material under treatment. Upon these cathode-frames I prefer to use thin foils of the metal that is to be precipitated, these thin foils being held in position by a board or coarse cloth attached and stretched over the frames and to which they adhere by the use of a cement or wax or other sticking material. 15 For copper I use copper-foil, for silver I use silver-foil, and for gold I use gold-foil.

Upon the bottom D of the tank A is placed a wooden frame Q to support the anodes, which consist of the two slotted sheets of lead 20 R and the carbon blocks S, which are placed between them, the upper sheet resting directly upon the blocks, which in turn rest upon the lower sheet R. These sheets of lead are provided with any desired number of radial slits or slots of any desired width, length, or shape, and the blocks S are placed upon edge and separated sufficiently far to allow the electrolyte to pass freely up and down between them. The lower sheet R is provided 25 with a connection W, which projects beyond the tank for connection with the general circuit.

Through opposite sides of the tank A, one being located at the bottom and the other at 30 the top of the tank, are two openings T, through which the electrolyte is made to pass in either direction, according as an up or down movement is desired. Suitable means are applied to opposite outsides of the tank 35 at the openings T for the purpose of forcing the electrolyte back and forth through the openings, as may be desired. By forcing the electrolyte material through the lower opening T it will pass through the upper opening 40 45 T upon the opposite side of the tank, and then when allowed to flow back the motion of the material is reversed, and thus a constant up-and-down back-and-forth movement through the tank is or may be kept up. 50 This up or down movement is given to the electrolyte back and forth through the tank in addition to the rotary movement which may be imparted to it by means of the revolving frames L, and hence it will be seen 55 that the electrolyte has a compound movement. The openings allow fresh electrolyte to be added while the cell is in operation and the lower opening allows the electrolyte to be freely drawn off at any time desired. 60 By my construction I avoid the fast destruction of the anodes, protecting them from outside injury or influence, and I obtain a most even and regular work and action between the cathode and anode. I also prevent 65 eddies, whirlpools, or irregular or accidental motion to the solution, which are at all times so detrimental in creating unforeseen resist-

ance. I also decrease the cause of accidental currents and precipitate the metals directly upon the cathode-plates in solid metallic 70 shape and not in a pulpy or slimy precipitate. The removal of the electrolyte takes place very promptly, as soon as it has been acted upon by the current and has deposited its quota of metal upon the cathode-plates. The 75 main feature of my invention consists in the helical flow of the electrolyte obtained by the combination of the regular ascending and descending flow of the electrolyte, combined with the circular motion imparted by the 80 cathode-frames. I also obtain a more uniform action in the use of the current, and also a large decrease in the resistance offered by the dissociation of the positive and negative irons. I also obtain a continuous working process, and consequently a most important saving in time and manipulation. 85

By my arrangement of the anodes in the bottom of the cell and causing the cathodes to revolve at a suitable distance above the anodes, thus bringing the parts uniformly and symmetrically opposite each other, there is less risk of accidental currents taking place, and the precipitation of the metals takes place directly upon the cathode-plates in solid me- 90 tallic shape. 95

By the use of a wheel and the cathode-frames connected therewith the cathode-frames are supported in position above the anodes and allow the use of any kind of cathode-electrodes, and the cathode-plates and the electrodes are made independent of the tank, and the tank serves no other purpose than an inclosing vessel that does not take part in the electrical nor chemical action during the process of electrolysis. 100

It is not necessary to take apart any portion of the parts of the cell to remove the cathodes when sufficiently loaded with metal or to put new cathode-plates in position. This 105 cell is adapted to the electro deposition or precipitation of all metals when they are in the solution in a proper electrolyte. The cell is complete in itself and does not require any additional machinery or appliances to perform its work, there being no partitions, filters, strainers, or other similar devices between the cathode and the anode. I produce a one-compartment cell and eliminate the 110 most of the resistance to the electric current 115 due to their presence and which is always 120 costly to overcome.

The electrolyte having both a rotary and an up-and-down movement it has free access to all parts of the cell, and the compound movement not only mixes it and gives it more uniformity, but assists in bringing every one of its molecules in contact with the surface of the cathode-plates. 125

The electrolyte by its helical motion remains in contact with the cathode-plates for a longer period of time than if the cathode-plates were stationary. The openings T upon opposite sides of the tank afford the possi- 130

bility of reversing the flow of the electrolyte from an upward to a downward motion should the specific gravity increase or decrease after being acted upon by the electric current. For instance, should an electrolyte be used whose component would be protochlorid of copper, the result would be a solution of bichlorid, which, being heavier, would sink to the bottom of the tank, and consequently would require a downward flow. On the other hand an electrolyte of cyanid of potassium being freed of its gold and becoming lighter requires an upward motion. In both cases it is very urgent to get rid as soon as possible of the parts of the electrolyte which have been acted upon by the electric current, and this is one of the principal features of my invention. The flow of the electrolyte and its velocity can be regulated at will, and the circular and regular motion imparted to the solution without violent action is a cause of economy in the electric current eliminating other mechanical force and part of the resistance. The surfaces of the cathodes and anodes can be modified at will by adding or suppressing any cathode-plate at any time during the process.

A cell constructed as here shown and described in a small volume can accomplish more work in presenting more cathode and anode surfaces to the action of the electric

current than under other forms of cells, and the work is accelerated.

The whole cell can be opened, taken apart, and cleaned up most easily and in a very short time can be put together again in working order without the use of extra labor or machinery.

Having thus described my invention, I claim—

1. In a cell for the precipitation of metals, 40 a tank, a revolving frame mounted thereon for carrying the cathode, combined with the anode, consisting of two slotted lead plates, one of which is connected with the circuit, a series of carbon blocks placed between them, 45 the cathode elements, and electrical connections, substantially as set forth.

2. In a cell for the precipitation of metals, the anode consisting of two slotted lead plates one of which is connected with the circuit, a 50 series of carbon blocks placed between them, the cathode element and the electrical connections substantially as set forth.

In testimony whereof I affix my signature in presence of two witnesses.

JOSEPH LUCE.
